No. 36,713.

Patented December 29, 1903.

UNITED STATES PATENT OFFICE.

JEREMIAH VANDERBILT, OF NEW YORK, N. Y., ASSIGNOR TO THE WILL & BAUMER COMPANY, OF SYRACUSE, NEW YORK, A CORPORATION OF NEW YORK.

DESIGN FOR A LAMP-SHADE.

SPECIFICATION forming part of Design No. 36,713, dated December 29, 1903.

Application filed September 19, 1903. Serial No. 173,900. Term of patent 3½ years.

To all whom it may concern:

Be it known that I, JEREMIAH VANDERBILT, a citizen of the United States, residing in the city of New York, county of New York, and

5 State of New York, have invented a new, original, and ornamental Design for Lamp-Shades, of which the following is a specification, reference being had to the accompanying drawings, in which—

10 Figure 1 is a top plan view thereof. Fig. 2 is a side view thereof.

What I claim is—

The ornamental design for a lamp-shade as shown.

In witness whereof I have hereunto set my hand on this 14th day of September, 1903.

JEREMIAH VANDERBILT. [L. S.]
